UNITED STATES PATENT OFFICE.

EVERETT E. WARNER, OF HARTFORD, CONNECTICUT.

AEROPLANE.

No. 893,887.

Specification of Letters Patent.

Patented July 21, 1908.

Application filed April 1, 1908. Serial No. 424,582.

To all whom it may concern:

Be it known that I, EVERETT E. WARNER, a citizen of the United States, residing at Hartford, in the county of Hartford and State of Connecticut, have invented a new and useful Aeroplane, of which the following is a specification.

This invention relates to the construction and arrangement of the kite or flight sustaining and guiding wings, flaps and planes of an aeroplane.

The object of this invention is to provide a very simple, cheap and light construction which is stable and which is so buoyant that it requires but a comparatively small amount of power to sustain and control its flight.

The embodiment of the invention illustrated by the drawings and described herein has an adjustable tip or steering head with vane-like supporting and current directing flaps adjacent to the head, a supporting or kite surface, the major part of which is back of the middle, an adjustable flap or tail piece for assisting the control of the upward and downward direction of flight, and side wings for assisting the control of flight across the wind. The lifting and propelling wings and the car with the mechanism for operating the wings are not illustrated, for they form no part of the present invention. The elevating wings, may, if desired, be such as are shown and described in Patent No. 881,836 issued to myself on March 10, 1908. The car may be formed of any light material suitably hung beneath the plane.

Figure 1 of the accompanying drawings shows a plan of one form of an aeroplane which embodies the invention. Fig. 2 shows an edge view of the same and Fig. 3 shows a view looking at the front end of the head of the plane.

The main frame of the form of invention illustrated consists of a longitudinally extending back-bone 1, a transversely extending body rib 2, a transversely extending head rib 3 and a transversely extending tail rib 4. These parts may be securely connected in any suitable manner and may be made of such light wood as bamboo, or may be made of light metal such as aluminum formed into tubular or other cross sectional shapes, which have the necessary strength and requisite lightness. The ends of these ribs are guyed and stayed preferably by wires or

cords 5. The stays can of course be made of other material if desired.

Below the frame and fastened to the body rib 2 and tail rib 4 and the guys 5 is a sheet 6 of thin light material, such as oil-silk, which forms the main body or kite section of the aeroplane. This section, the major part of which is back of the middle, and which is preferably wider at the front end than at the rear end, may, if desired, be made of other fabric having suitable strength and lightness or may be made up of feathers.

Under the bow section of the main frame, which in the form shown is narrowest at the front end, are arranged a number of flaps or vanes 7. In the device shown there are two of these vanes, and they are preferably formed of oil-silk but may be formed of other strong light fabric or feathers. The forward of these vanes is attached at its front edge to the head rib 3 and the rear vane has its front edge attached to the transverse wire or cord 8. The side edges and rear edges of these vanes are preferably free, and the rear edge of the front vane underlaps the front edge of the vane back of it, so that the rear edges of the vane can drop down. Wires or cords 9, 10 and 11 are arranged transversely across the bow section for the purpose of staying and guying the frame, and these hold the vanes from being lifted above the plane of the frame. Between the flaps or vanes of the bow section and the main body is an opening 12 in which the lifting and propelling wings previously referred to, but not shown, are designed to be located.

The tip or head section which is preferably pointed at the bow has a frame built of a longitudinal rod, tube or bar 13 of any suitable material and a transverse bar 14 of similar material. These bars are guyed and stayed by wires or cords 15 and the head is connected with the main frame preferably by a universal joint 16. Cords or wires 17 and 18 lead from the tip of the head around the ends of a vertical yard or cross-tree 19 and through a sheave 20 to the car in such manner that by manipulating these cords or wires the head can be held in, or inclined above or below the plane of the frame, as shown in dotted lines in Fig. 2. Cords or wires 21 and 22 may be led from the ends of the cross bar 14 of the head to the ends of the yard 19 and back through the sheave 20 to the car for the purpose of holding the head in the plane of, or

oscillating it transversely with relation to the plane of the frame, as indicated in Fig. 3. The head frame is covered with a sheet 23 of oil-silk, feathers or like light material.

5 The tail section has a light longitudinal rib 24 of suitable material, hinged to the main frame by a joint 25 so that it may be oscillated up or down with relation to the plane of the main frame. This rib is stayed

10 or guyed by a wire or cord 26. Secured to this tail frame is the tail which is formed of a piece 27 of oil-silk, feathers or similar light material. Cords or wires 28 and 29 may lead from the central rib 24 around the ends 15 of the vertical cross-tree or yard 30 through the sheave 20 to the car for the purpose of holding the tail in the plane of, or oscillating it above or below the plane of the main section of the body.

20 At the ends of the main transverse rib 2 are hinged rods or tubes 31 to which are connected flag-like wing sections 32 of silk, feathers or the like. The side and rear edges of these flag-like sections are preferably free 25 and connected with the rods 31 are cords or wires 33 which lead through the sheave 20 to the car for the purpose of swinging the wings in or out, as illustrated in Fig. 1. Similar flag-like wings 34 may be arranged at the 30 rear end of the body in the same way and provided with cord or wires 35 by means of which these wings may be positioned.

When this aeroplane is in motion the head 35 may be tilted up or down for the purpose of causing the flight to be deflected upwardly or downwardly and the tail may also be elevated or depressed to assist in directing the plane upwardly or downwardly. The head may also be oscillated transversely for changing 40 the course of the plane or for compensating for the direction of the wind. The flag-like wings are moved inwardly or outwardly according to the direction of the wind, that is, if the wind is blowing across the plane the 45 flags on the windward side are drawn in, and the flags on the leeward side are moved outwardly. During flight the free rear edges of the transverse vanes or flaps tend to hang downwardly. If the plane is falling or the 50 air currents are greatest from beneath, the vanes close and provide a supporting surface. If the plane is rising or the air currents are greatest from above, the vanes slightly open and allow the air to pass through and strike 55 against the main kite back of the center and tend to lift it and keep it on a horizontal plane.

The invention claimed is:

1. An aeroplane having a main frame, a 60 kite-like supporting surface attached to the frame mainly back of the middle, a tail attached at the stern, a head attached at the bow and vanes back of the head, with a space between the vanes and the main kite, substantially as specified.

2. An aeroplane having a main frame, a kite-like supporting surface attached to the frame mainly back of the middle, a tail attached at the stern, means for oscillating the tail upwardly and downwardly with relation 70 to the plane of the main kite, a head attached at the bow and vanes back of the head, with a space between the vanes and the main kite, substantially as specified.

3. An aeroplane having a main frame, a kite-like supporting surface attached to the frame mainly back of the middle, a tail attached at the stern, a head attached at the bow, means for oscillating the head upwardly and downwardly with relation to the plane 80 of the main kite, and vanes back of the head, with a space between the vanes and the main kite, substantially as specified.

4. An aeroplane having a main frame, a kite-like supporting surface attached to the frame mainly back of the middle, a tail attached at the stern, means for oscillating the tail upwardly and downwardly with relation to the plane of the main kite, a head attached at the bow, means for oscillating the head upwardly and downwardly with relation to the plane of the main kite and vanes back of the head, with a space between the vanes and the main kite, substantially as specified.

5. An aeroplane having a main frame, a kite-like supporting surface attached to the frame mainly back of the middle, a tail attached at the stern, means for oscillating the tail upwardly and downwardly with relation to the plane of the main kite, a head attached at the bow, means for oscillating the head transversely of the plane of the main kite and vanes back of the head with a space between the vanes and the main kite, substantially as specified.

6. An aeroplane having a main frame, a kite-like supporting section attached to the frame mainly back of the middle, a tail attached at the stern, a head attached at the bow, means for oscillating the head upwardly and downwardly, means for oscillating the head transversely with relation to the main kite and vanes back of the head with a space between the vanes and the main kite, substantially as specified.

7. An aeroplane having a main frame, a kite-like supporting surface attached to the main frame mainly back of the middle, a tail attached at the stern, means for oscillating the tail above or below the plane of the main kite, a head attached at the bow, means for oscillating the head upwardly or downwardly and means for oscillating the head transversely with relation to the main kite and vanes back of the head with a space between the vanes and the main kite, substantially as specified.

8. An aeroplane having a longitudinally extending backbone with transverse ribs, a supporting surface attached to the frame

mainly back of the middle, a tail frame hinged to the main frame, a tail attached to the tail frame, a head frame hinged and pivoted to the main frame, a head surface attached to the head frame, and vanes attached to the main frame back of the head, substantially as specified.

9. An aeroplane having a main frame, a kite-like supporting surface attached to the frame mainly back of the middle, a tail frame attached to the main frame, a tail sup-

ported by the tail frame, a head frame attached to the main frame, a head attached to the head frame, vanes attached to the main frame back of the head and wings 15 hinged to and projecting outwardly from the main frame, substantially as specified.

EVERETT E. WARNER.
